United States Patent Office

Des. 210,756
Patented Apr. 9, 1968

210,756

HEATER CABINET

Robert L. Miller, Centralia, Ill., assignor to Lear Siegler,
Inc., Santa Monica, Calif., a corporation of Delaware

Filed June 23, 1966, Ser. No. 2,784

Term of patent 14 years

(Cl. D81—19)

FIG. 1

FIG. 2

FIG. 1 is a front elevated view of a heater cabinet showing my new design; and

FIG. 2 is a side elevational view of FIG. 1.

The side opposite to that shown in FIG. 2 is the same in appearance as that shown in FIG. 2.

I claim:

The ornamental design for a heater cabinet, as shown and described.
